UNITED STATES PATENT OFFICE

137,594

DESIGN FOR A GAME BOARD

Joseph I. Galantin, Des Plaines, Ill.

Application September 6, 1943, Serial No. 111,072

Term of patent 7 years

(Cl. D34—5)

To all whom it may concern:

Be it known that I, Joseph I. Galantin, a citizen of the United States, residing at Des Plaines, in the county of Cook and State of Illinois, have invented a new, original, and ornamental Design for a GAME BOARD, of which the following is a specification, reference being had to the accompanying drawing forming part thereof.

In the drawing:

I claim:

The ornamental design for a game board, as shown.

JOSEPH I. GALANTIN.
